[57] CLAIM

The ornamental design for a carrying case for tape cartridges and cassettes, substantially as shown and described.

DESCRIPTION

FIG. 1 is a perspective view of a carrying case for tape cartridges and cassettes showing my new design;

FIG. 2 is a perspective view thereof in an open condition;

FIG. 3 is a top plan view in the open condition;

FIG. 4 is a rear elevational view in the open condition;

FIG. 5 is a right end elevational view in the open condition, the opposite side being a mirror image thereof; and

FIG. 6 is a bottom plan view in the open condition.
